BICYCLE HANDLEBAR

Viktor Schreckengost, Cleveland Heights, Ohio, assignor
to The Murray Ohio Manufacturing Co., Nashville, Tenn., a corporation of Ohio

Filed Dec. 11, 1968, Ser. No. 14,909

Term of patent 14 years

Int. Cl. D12—14

U.S. Cl. D90—11

Fig. 1

I claim:

The ornamental design for a bicycle handlebar, substantially as shown.
